UNITED STATES PATENT OFFICE.

GUSTAV GEIGER, OF MUNICH, GERMANY.

HANDLE FOR PHOTOGRAPHIC STICK-STANDS.

SPECIFICATION forming part of Letters Patent No. 744,526, dated November 17, 1903.

Application filed February 20, 1903. Serial No. 144,313. (No model.)

To all whom it may concern:

Be it known that I, GUSTAV GEIGER, chemist, a subject of the King of Bavaria, and a resident of No. 32 Herzog-Wilhelmstrasse, in 5 the city of Munich and Kingdom of Bavaria, Germany, have invented certain new and useful Improvements in Handles for Photographic Stick-Stands, of which the following is a specification.

10 The object of the present invention relates to a handle to be attached to stick-shaped stands or supports as used for carrying photographic apparatus. There are many handles of this kind and of a great variety of 15 construction; but with the majority of these the chief attention has been paid to solidity of construction only, whereas simplicity and handiness leave still much to be desired.

A great drawback with the stick-stands in 20 general use at present is the necessity of screwing off and exchanging the handle with a head or top piece required for the support, and, further, no provision has been made for a sufficiently-broad basis or rest for the photographic apparatus. To remove these drawbacks and produce a perfect stand is the 25 object of the present innovation. The essential feature of it is that a flat bar contained in the handle and covered in the same by an arched lid can be set or adjusted crosswise to the handle, so as to form a cross with the latter, and thus constitute a broad and firm rest for the apparatus.

On the accompanying drawings the object 30 of the invention is illustrated.

Figure 1 shows a side view of the handle, partly in section; Fig. 2, a cross-section through the middle of Fig. 1; and Fig. 3 shows the handle in use—in other words, supporting the photographic apparatus, which is indicated by dash-lines.

Similar letters refer to similar parts throughout the several views.

The handle of the stand consists of the 45 lower or bottom part *a*, provided with a threaded socket *b* for the stand and which can be made of any suitable material. On the part *a* rests the flat bar *c*, which is of the same breadth as *a* and is journaled in its 50 center upon the bolt *d*. The bolt *d* has at its

upper end a threaded projection *e*, serving to secure the photographic apparatus to the handle. The part *a* has in the center a recess *f* of the same depth as the thickness of the flat bar *c* and of the width of the latter. 55 Thus said bar *c* can when placed crosswise be kept in the recess *f*. In order to give the whole the appearance and form of an ordinary handle of a walking-stick, there has been provided at the bottom part *a* an arched lid *g* in a turning-joint *h*, which lid incloses the device and can catch in a notch on the opposite side of the turning-joint *h* on the part *a*. In the lid *g* I may arrange two light springs in order to prevent a rattling of 60 the flat bar *c* on the stick being used in walking, as these springs will press the flat bar *c* against the part *a*. In order to allow of turning the photographic apparatus on the support in all directions, the threaded socket *b* 70 has at its upper end an inwardly-burnished bur-shaped rim *i*, which engages the material of the bottom part *a*. A corded ring *k* actuates the rotation and serves also to screw the socket *b* onto the support. 75

If the device is to be used, the lid *g* is opened and the flat bar *c* thereupon turned ninety degrees, so that it engages into the recess *f*, when the apparatus is screwed upon the pin *e* so that the bottom of the apparatus 80 rests at the same time on *a* and *c*, Fig. 3.

The parts *a* and *c* may be lined in the usual manner with velvet or other material in order to prevent the apparatus from getting damaged and to make it stick to the support. 85

What I claim as my invention, and desire to secure by Letters Patent of the United States, is—

1. The combination in a handle for photographic stick-shaped stands with a bottom part *a* having a threaded socket *b* with the sector *f*, a flat bar *c* turning on its center with the pin *e* for screwing on the photographic apparatus, substantially as set forth. 90

2. A handle for photographic stick-shaped stands, with the bottom part *a*, the arched or vaulted lid *g* on the turning-link *h* for covering the inner arrangement of the handle, substantially as set forth. 95 100

3. A handle for photographic stick-shaped stands, with the bottom part *a*, a crown or rim *i* entering like claws into the threaded socket *b* for turning the apparatus and a 5 corded ring *k* for screwing on the handle, substantially as and for the purpose set forth.

In testimony whereof I have signed my

name to this specification in the presence of two subscribing witnesses.

GUSTAV GEIGER.
